DESIGN FOR A KEY CASE OR THE LIKE

Nicholas A. Mercer, New York, N. Y.

Application June 15, 1938, Serial No. 77,848

Term of patent 7 years

To all whom it may concern:

Be it known that I, Nicholas A. Mercer, a citizen of the United States, residing at 101 West 76th Street, in the city of New York, in the county of New York, and State of New York, have invented a new, original, and ornamental Design for Key Cases or the Like, of which the following is a specification, reference being had to the accompanying drawing, forming part thereof.

I claim:

The ornamental design for a key case or the like, as shown and described.

NICHOLAS A. MERCER.
